CREEL

Fritz Lambach, Tenafly, N. J., assignor to Robert Reiner, Inc., Weehawken, N. J.

Application February 8, 1945, Serial No. 576,764

2 Claims. (Cl. 242—131)

1

My invention relates to textile machines, and more particularly to creels, which are customarily used in conjunction with warpers or beamers for the winding of yarn from bobbins on a beam.

Creels of this type are equipped with holding means for holding a plurality of bobbins and with carrying means for carrying a plurality of yarn tensioning devices or so-called "tensions" exerting a braking action on the yarns running from the bobbins to the beam in the warper or beamer.

An object of my invention is to provide a creel of above described type with a tension rack for carrying the yarn tensioning devices or "tensions," which may be readily brought into different positions relative to the holding means holding the bobbins.

Another object of my invention is to build a creel of above described type in such a way that the tension rack carrying the yarn tensioning devices does not comprise elements forming a part of the frame structure of the creel, so that the tension rack may be brought into different position without weakening the frame structure of the creel during such a displacement of the tension rack.

A further object of my invention is to provide a creel with means permitting an extremely fine and accurate control of the so-called "balloon of the yarn."

Still another object of my invention is to provide a creel, which may be readily adapted to various loads of bobbins for various winding operations.

A further object of my invention is to improve upon the construction of creels as now ordinarily made.

My invention consists in certain novel features of creels as will be fully described hereinafter.

Further objects and advantages of the invention will be apparent from the following disclosure of several embodiments thereof.

In the accompanying drawings is:

Fig. 1, a somewhat diagrammatical top plan view of a creel according to the invention,

Fig. 2, a front elevational view of the creel shown in Fig. 1, in an enlarged scale,

Fig. 2a, a sectional view of a detail of the creel illustrating the controlling means of a stop motion,

Fig. 3, a sectional view taken on line 3—3 of Fig. 2,

Fig. 4, a top plan view of the first section of the creel shown in Fig. 1, in an enlarged scale,

Fig. 5, a sectional view taken on line 5—5 of Fig. 4,

2

Fig. 6, a top plan view of a different embodiment of a creel according to the invention,

Fig. 7, partly a front elevational view, partly a sectional view of the creel shown in Fig. 6, taken on line 7—7 of Fig. 6, in an enlarged scale,

Fig. 8, a sectional view taken on line 8—8 of Fig. 6, in an enlarged scale, and

Fig. 9, an elevational view of a detail of the creel shown in Fig. 7, in an enlarged scale.

Referring now to Figs. 1—5, 20 generally indicates a creel, which is composed of four sections I, II, III, IV detachably connected with each other at 22, 24, and 26. Each section comprises a supporting frame generally indicated by 28^I, 28^{II}, 28^{III}, and 28^{IV}, on either side of which a tension rack generally indicated by 30^I, 30^{II}, 30^{III}, and 30^{IV} is shiftably mounted in a manner to be described hereinafter. The first sectional supporting frame 28^I at the end of the creel opposite the warper or beamer (not shown) is of tapered shape, while the remaining sectional supporting frames 28^{II}, 28^{III}, 28^{IV} are substantially in the shape of a rectangle. For an understanding of the invention it is sufficient to describe in detail the section I of the creel, as the sections II, III and IV are constructed according to the same principle as section I.

As best shown in Figs. 2 and 4, the sectional supporting frame 28^I is built by longitudinal channels 32, 34, uprights 36, bracing members 38, and traverse channels 40, 42 rigidly connected with each other in a suitable manner, for example by screws or rivets, so that this sectional supporting frame 28^I forms a rigid structure or unit. Said supporting frame 28^I is provided with two rows of vertical holding means or rods 44 connected to the upper and lower longitudinal channels 32, 34. Series of holders 46 for holding bobbins 48 (only one being shown in Fig. 4) may be attached to said vertical rods 44 in a manner known per se.

As best shown in Figs. 1 and 4, a first transverse channel 50 and a second transverse channel 52 are mounted on top of the upper longitudinal channels of the sectional supporting frame 28^{II}, which is of substantially the same construction as above described sectional supporting frame 28^I and may be rigidly connected with the latter by screws 22. Likewise, as shown in Fig. 1, a similar transverse channel 54 is screwed to the upper longitudinal channels of the sectional supporting frame 28^{III}, which may be rigidly connected with the sectional supporting frame 28^{II} by screws 24, and another transverse channel 56 is secured to the top of the sectional supporting

frame 28^{IV}, which may be rigidly connected with the sectional supporting frame 28^{III} by screws 26. The transverse channel 40 on the sectional supporting frame 28^I in conjunction with the transverse channel 50 on the sectional supporting frame 28^{II} form spaced tracks for the tension racks 30^I of the section I in a manner to be described hereinafter; likewise, the transverse channel 50 in conjunction with the transverse channel 52; the transverse channel 52 in conjunction with the transverse channel 54, and the transverse channel 54 in conjunction with the transverse channel 56 form spaced tracks for the tension racks 30^{II}, 30^{III} and 30^{IV} respectively. There are no transverse connecting elements between the inner longitudinal channels 34 at the bottom of the creel, so that trucks with a load of bobbins to be placed on the holders 46 of the creel may be rolled without hindrance into the inside space of the creel between the uprights 36.

As best shown in Figs. 2, 4 and 5, each tension rack 30^I is formed by an upper longitudinal channel 58 and a lower longitudinal channel 60 rigidly connected with each other by a row of vertical rods or carrying means 62 passing through openings of the channels 58, 60 and held in position by nuts screwed to the threaded ends of the rods. Series of yarn tensioning devices or so-called "tensions" 64 (only one being shown in Figs. 4 and 5) may be attached to said vertical rods 62 of the tension rack 30^I in a manner, known per se. Spaced hook-like engaging elements 66 are secured to the upper channel 58 of the tension rack at opposite ends thereof. Furthermore, a bracket 68 is secured to the front end of the upper channel 58, and another bracket 70 is secured to the lower channel 60. Said brackets 68 and 70 are provided with registering holes for receiving a vertical rod or post 72, which may be secured to said brackets by means of a set screw 74. A row of arms 76 provided with eyelets 78 and capable of carrying electrical controlling means or drop wires of a stop motion for arresting the warper or beamer upon breakage of yarn, is mounted on each post 72. Fig. 2a illustrates the arrangement of the electrical controlling means in more detail. A drop wire 79 provided with an eyelet 81 for the passage of the yarn 87 coming from the eyelet 78 of an arm 76 is swingably mounted on a rod 83 carried by a bracket 77 secured to the arm 76. Said rod 83 is electrically connected with one line 75 of an electric circuit of the stop motion. A second rod 85 carried by an insulating element 73 mounted on the bracket 77 is electrically connected with a second line 71 of the electric circuit. Upon yarn breakage the drop wire 79 drops, swinging about the rod 83, until it abuts against the rod 85, thus causing a closing of the electric circuit of the stop motion, whereby, in a manner known per se, the warper or beamer is stopped. Said arms 76 are adjustable, and may be held in an adjusted position by means of set screws 80. Said adjustable arrangement of the arms 76 on the parts 72 permits an adjustment of said arms in upward and downward direction whereby the drop wires 79 may be brought into a suitable plane with respect to the tensioning devices 64 and bobbins 48. Furthermore, said adjustable arrangement of the arms 76 on the posts permits a swinging of said arms around said posts whereby they may be adjusted in such a position that the angle between the oncoming end of the yarn (coming from the tensioning device) and the arm and the angle between the leaving end of the

yarn (travelling normally at an angle to the longitudinal axis of the creel toward the warper or beamer) and the arm may be made of equal value so as to obtain a smooth running of the yarns.

A tension rack 30^I of above-described construction is shiftably suspended from the transverse channels 40 and 50 on each side of the creel by means of the spaced engaging elements 66, slidably engaged with said channels 40 and 50. As may be gathered from Fig. 2, the lower channels 60 of the tension racks 30^I are at a distance from the floor, so that the tension racks 30^I may be freely moved in sidewise direction. It is emphasized, that the tension racks 30^I do not form a part of the supporting frame 28^I proper, so that a displacement of the tension racks from one position into another one may be easily carried out without causing a weakening of the structure of the supporting frame.

The outermost position of the tension rack 30^I is limited by stops 82, 84 on the transverse channels 40 and 50 respectively, while the innermost position of the tension rack is limited by the upper longitudinal channel 32. The structure of the tension rack abuts against said stops 82 and 84, or against said upper channel 32 in one or the other of said extreme positions.

The shiftable arrangement of the tension racks 30^I of the creel shown in Figs. 1-5 may be readily used for a fine and accurate control of the balloon 86 of the yarns 87 drawn from the bobbins 48. As a matter of fact, yarns of different weight and quality form balloons of different sizes. Consequently, it is desirable to change the distance between the carrying means or rods 62, carrying the yarn tensioning devices 64, and the holding means or rods 44, holding the bobbins 48, in accordance with the size of the balloon 86 in such a manner, that the apex of the balloon substantially coincides with a yarn receiving guiding aperture 89 of a yarn tensioning device 64.

As shown in Figs. 2-5, an arm 88 having a slot 90, is secured to the lower channel of the tension rack 30^I by means of a screw 92 at each end thereof. An adjusting screw 94, passing through said slot 90 of the arm 88 is screwed into a threaded bore of the lower channel 34 of the supporting frame 28^I. As clearly shown in Fig. 3, a scale 96 is arranged along the slot 90. Figs. 2 and 4 illustrate the tension racks 30^I in their outermost position. If the creel is to be used for bobbins with yarn of different quality forming a balloon of different size, the operator may readily shift the tension racks into a different position, for example into the position shown in dash and dot lines in Fig. 2 and in full lines in Fig. 3 after loosening the adjusting or positioning screw 94. According to instructions, given to the operator, the operator determines the new position of the tension rack by means of the scale 96, and when this new position is reached, the screw 94 is tightened, so that the tension rack 30^I is held in the proper position. As will be readily understood, the tension rack 30^I may be brought into any position between its two extreme positions.

The construction of the tension racks 30^{II}, 30^{III}, and 30^{IV} of the sections II, III and IV substantially corresponds to the construction of above-described tension rack 30^I of the section I. The arms 98, 100, 102 (see Figs. 1, 4 and 5) which are secured to vertical bars, mounted on the tension racks, carry only eyelets for the passage of the yarns and are somewhat smaller than the

arms 16 attached to the tension rack 30^I. Each of the tension racks 30^{II}, 30^{III}, 30^{IV} is equipped with spaced hook-like engaging elements at opposite ends of its upper channel. The tension racks 30^{II} are shiftably suspended from the transverse channels or tracks 50, 52 by means of said engaging elements, the tension racks 30^{III} are shiftably suspended from the transverse channels or tracks 52, 54 by such engaging elements, and the tension racks 30^{IV} are shiftably suspended from the transverse channels or tracks 54, 56 by means of such engaging elements.

If the four sections I, II, III, and IV are connected with each other as shown in Fig. 1, the creel may be used for a certain maximum capacity of bobbins. If, for a certain warping operation, a smaller amount of bobbins is to be held by the creel, the sections III and IV, for example, may be disengaged from sections I and II.

Figs. 6-9 illustrate a different type of a creel 104, a so-called truck creel, which is equipped with shiftably mounted tension racks 106, 108 according to the invention. 110 generally indicates the supporting frame of the creel 104, which is built by a plurality of tubular members 112, 114, 116, 118, 120, 122, 124, 126, 128, 130, 132, 134, 136, 138, 140, 142, 144, 146, 148, several transverse bars 150, 152, 154, 156, 158, 160, and several transverse channels 162, 164, 166, 168, 170, 172, 174, 176, rigidly connected with each other in a suitable manner, so that this supporting frame forms a rigid structure or unit. Said supporting frame 110 is provided with guiding rails 178 for cooperation with trucks 180, carrying a plurality of bobbins 182. Said trucks, when loaded with full bobbins, may be rolled into the creel. When the bobbins are used up, the trucks may be removed, and may be returned into the creel when reloaded with fresh bobbins.

According to Figs. 6-9, pairs of spaced tracks 184 are mounted on the transverse channels 162, 164, 170, and 172 of the supporting frame 110. Likewise, pairs of spaced tracks 106 are attached to the transverse channels 166, 168, 174 and 176 of the supporting frame 110. Above-mentioned sectional tension racks 106 are shiftably suspended from said pairs of tracks 124 on each side of the creel in a manner to be described hereinafter, and, likewise, the sectional tension racks 108 are shiftably suspended from said pair of tracks 166 on each side of the creel.

As best shown in Figs. 6-8, the tension rack 106 comprises an upper channel 188 and a lower channel 190, rigidly connected with each other by a row of carrying means or vertical rods 192. Series of yarn tensioning devices or so-called "tensions" 194 (only one being shown in Fig. 8) may be attached to said vertical rods 192 in a manner known per se. Furthermore, a bracket 196 is secured to the upper channel 188, and a bracket 198 is secured to the lower channel 190. Said brackets have registering openings for receiving a rod or post 200, which may be secured to said arms 196 and 198 in any suitable manner, for example by a set screw. A row of adjustable arms 202, equipped with eyelets 204 and capable of carrying electrical control means for a stop motion is attached to said post 200; said arms 202 may be held in their adjusted positions by means of set screws. A pair of spaced plates 206 is secured to opposite ends of the upper channel 188 of the tension rack 106. A pair of wheels 208 is journalled in suitable bearings of each of said plates 206. Said pair of plates 206 equipped with said wheels 208 form a carriage from which the

tension rack 106 is suspended. The wheels 208 of said carriage are engaged with the tracks 184, so that the tension rack 106 may be readily shifted in sidewise direction along said tracks 184.

- 5 As will be apparent from above, the tension racks 106 secured to and suspended from said carriage form separate units as no element thereof forms a part of the supporting frame 110 of the creel, so that said tension racks 106 do not cause a 10 weakening of the frame structure when they are moved in different positions.

In order to assure a movement of the carriage 206, 208 and the tension rack 106 secured thereto in a straight line and to prevent a twisting of the carriage during a shifting of the tension rack 106 from one position into another one, the following controlling means are arranged. A shaft 210 journalled in suitable bearings of the plates 206 carries at each of its ends projecting from the plates 206 a pinion 212, keyed to said shaft 210.

- 15 Each of said pinions 212 is in mesh with a rack 214, secured to one of the transverse channels 162, 164, 170 or 172. As will be readily understood, this controlling mechanism 210, 212, 214, assures a uniform movement of both ends of the 20 carriage 206, 208 and consequently of both ends of the tension rack 106, when the latter is shifted in sidewise direction.

As best shown in Figs. 7 and 9, the outermost 30 position of the tension rack 106 is limited by a stationary stop 216, arranged for engagement with one of the wheels 208. The innermost position of the tension rack 106 is limited by an adjustable stop 218, arranged for engagement 35 with the other wheel 208. Said adjustable stop 218 may be held in any desired position by means of a set screw 220 or the like, passing through a slot 222, arranged in the upper rail 184. A scale 224, arranged on each side of the slot, may be 40 used for setting the stop 218 in a predetermined position.

As best shown in Figs. 7 and 8, the lower channel 190 of the tension rack 106 is at a distance from the floor, so that the tension rack 106 may be freely moved along the tracks 184. If the creel 45 is built for a large capacity of bobbins, the arms 202 must be made of a rather large size, so that a rather considerable weight acts on the post 200. In order to relieve the tension rack 106 from said 50 weight, an arm 224 carrying a supporting roller 226 for engagement with the floor may be adjustably mounted at the lower end of the post 200 and may be held in its position by means of set screws 228.

- 55 The construction and arrangement of the sectional tension racks 108 substantially corresponds to above-described construction and arrangement of the sectional tension racks 106. The tension racks 108 are secured to and suspended from a 60 carriage, formed by the pair of plates 230, carrying the wheels 232. Said wheels 232 are engaged with the tracks 186 for movement along said tracks. The controlling means comprising a shaft 234 carrying pinions 236 in mesh with racks 238 65 assures a straight movement of the carriage 230, 232 along the tracks 186. A bracket 240, secured to the upper channel 242 of the tension rack 108 and a bracket 244 secured to the lower channel 246 of the tension rack 108 carry a vertical bar 70 248 for the support of a row of arms 250, equipped with eyelets 252 for the passage of yarn.

The movable arrangement of the sectional tension racks 106, 108 in a truck creel of the type, shown in Figs. 7-9 serves two purposes, i. e. the 75 purpose of facilitating the loading of the creel

and the purpose of the control of the balloon of the yarn. Fig. 7 illustrates the tension racks 106 and 108 in full lines in operating position. The space between the rods 192 of the tension rack 106 carrying the yarn tensioning devices and the bobbins 182 on the truck 180 as well as the space between the rods 254 of the tension rack 108, carrying the yarn tensioning devices and the bobbins 182 on the truck 180 is rather small, so that there is no access for the operator to enter the space between the yarn tensioning devices and the bobbins. Therefore, if the creel is to be loaded, the tension racks 106 and 108 are shifted into the position 106' and 108' shown in dash and dot lines in Fig. 7. If the loading operation is completed, the tension racks 106 and 108 are returned into their operating position shown in full lines in Fig. 7. If the yarns on the bobbins 182 form a balloon requiring a different distance of the tensioning devices carried by the rods 192 and 254 respectively from the bobbins 182, held by the truck 180, the adjustable stop 218 is brought into a different position, for example in the position 218'', shown in Fig. 9. In such a case, the innermost operating position of the tension racks determined by the stop now being in the position 218'' is at a larger distance from the bobbins 182, so that for example the rods 192 of the tension rack 106 are in the position 192'' shown in dash and dot lines in Fig. 9.

I have described preferred embodiments of my invention, but it is understood that numerous changes and omissions may be made without departing from the spirit of my invention.

For example, a creel of the type shown in Figs. 7-9 may be equipped with more than two sectional tension racks on each side thereof.

Furthermore, other controlling means than those shown in the drawings, may be provided for preventing a twisting of the tension rack during a shifting thereof.

Moreover, a creel of the type shown in Figs. 1-5 may be equipped with tension racks, secured to and suspended from a carriage of the type, shown in Figs. 7-9, or else other suitable means may be provided for to prevent a twisting of the tension racks in a creel of the type, shown in Figs. 1-5.

What I claim is:

1. In a creel with holding means for holding a plurality of bobbins, the combination of a supporting frame, at least one tension rack including carrying means for carrying a plurality of yarn tensioning devices, said tension rack being shiftably mounted on said supporting frame for an adjustment of the distance between said holding

5

means and said carrying means, a rod secured to said tension rack, and a plurality of arms for carrying series of electrical controlling means of a stop motion, each of said arms being adjustably mounted on said rod.

2. A creel comprising in combination: a plurality of disconnectable supporting frame sections, means for connecting said supporting frame sections with each other so as to form a supporting frame assembly, at least one series of holding means arranged in each supporting frame section for holding a plurality of bobbins, at least one tension rack including a series of carrying means for carrying a plurality of yarn tensioning devices associated with each supporting frame section, said tension racks being shiftably mounted on said supporting frame assembly for moving said yarn tensioning devices relative to said bobbins, each of said yarn tensioning devices having an aperture for the passage of yarn coming from a bobbin, and setting means including position indicating means associated with each of said shiftable tension racks whereby the latter with their carrying means may be set in such a predetermined position relative to said holding means holding the bobbins that the apex of the balloon made by a yarn drawn from a bobbin substantially coincides with the position of an aperture of a yarn tensioning device carried by such carrying means.
